CLAIM

The ornamental design for a mobile phone, as shown and described.

DESCRIPTION

FIG. 1 is a front perspective view of a mobile phone, showing my new design in a first state where a camera region is retracted;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a front perspective view of the mobile phone, showing my new design in a second state where the camera region is raised up;

FIG. 9 is a front view thereof;

FIG. 10 is a back view thereof;

FIG. 11 is a top view thereof;

FIG. 12 is a bottom view thereof;

FIG. 13 is a right side view thereof; and,

FIG. 14 is a left side view thereof.

The broken lines in drawings show portions of the mobile phone that form no part of the claimed design.

The stipple shading shown throughout the views define contrasting surfaces.
